UNITED STATES PATENT OFFICE.

DAVID MUSGRAVE EDWARDS, OF LONDON, ENGLAND.

COMBINED ELECTRIC PLUG AND SWITCH.

1,299,926.

Specification of Letters Patent.

Patented Apr. 8, 1919.

Application filed September 27, 1917. Serial No. 193,570.

To all whom it may concern:

Be it known that I, DAVID MUSGRAVE EDWARDS, a subject of the King of Great Britain, residing in London, England, have invented a certain new and useful Combined Electric Plug and Switch, of which the following is a specification.

The invention relates to a combination of an electric switch with a wall socket and plug of the type in which the plug is provided with means for operating the projecting handle of a tumbler or other switch to make and break the circuit, so that the switch is not "on" until the plug is pushed home and is "off" before the plug is withdrawn, so that a shock cannot be experienced in inserting and removing the plug and no sparking can occur at the plug contacts.

The invention differs from other previously known devices for this purpose in being adapted for easy application to switches of usual construction and mounting and for this purpose the wall socket and plug are fitted by the side of and adapted to be placed on the same support as the switch.

According to the invention a wing, or projection, on the plug engages, when the plug is inserted in the socket, with a plunger operating the switch and displaces it against the resistance of a spring.

The device according to the invention is very easily adapted to the conditions in which the plug and switch, or the switch only, are to be made water-tight, but it is also very useful, wherever circuits conveying currents are closed or opened by wall plug contacts, for example, for electric heating apparatus and for machine tools in workshops.

In the accompanying drawings, Figures 1 and 2 are, respectively, a sectional elevation and a plan of an example of a combined wall socket plug and switch according to the invention in which the combination is made water-tight. Fig. 3 shows the plug removed and replaced by a cap. Figs. 4 and 5 show modifications in which the parts are not inclosed in a water-tight casing.

In the example shown in Figs. 1-3, 1 is a plug contact device of usual construction, but provided on one side with a wing projection 2 adapted to engage with a plunger 3 sliding in a tubular guide 4 bolted by flanges 5 to the cover 6 of a metal casing 7, in which is inclosed a tumbler switch 8 of usual type.

Contact pins 9 and 10 of the plug 1 engage in well-known manner with tubular contacts in a porcelain socket 11. The socket 11 is inserted in a short metal tube 12 screw-threaded externally and secured to the cover of the casing 7 by a flange 13. A circular nut 14 engaging with the thread of the tube 12 and provided with a milled head serves to compress a rubber packing ring 15 to prevent any access of water to the socket. If the fit of the plunger 3 in the tube 4 is not sufficient to prevent water finding its way to the switch contacts a packed gland may be provided. A recess 16 in the plunger 3 engages with the pip 17 of the tumbler switch 8 and the arrangement is such that as the plug 1 is inserted in its socket, the plunger is displaced by the wing 2 against the resistance of a spring 18 to close the switch contacts 19, which are only completed when the plug contacts have been pushed home.

On the withdrawal of the plug, the plunger 3 is rapidly forced back by the spring 18 and by the action of the switch springs the contacts 19 are released before the plug contacts have been withdrawn, so that no sparking at the plug contacts or shocks to the operator are possible either on the insertion or the withdrawal of the plug.

Fig. 1 shows in full lines the position of the plunger when the plug is inserted and the tumbler switch is closed; the positions of the plunger and of the wing projection 90 of the plug just before the insertion of the latter are shown by the dotted lines.

The helical spring 18 can be replaced by another suitable form, for example, by a plug of rubber or other elastic material.

As shown in Fig. 3, when the plug 1 is not in use, the socket can be closed by a metal cap 20 provided with an internal screw thread engaging with the thread on the tube 12.

The modifications shown in Figs. 4 and 5 are suitable for conditions which do not require that the parts should be water-tight. Similar parts are denoted by the same references as in the preceding figures.

In the device shown in Fig. 4, a spring 18 may be inserted in the tube 4 as shown in Fig. 1, but this spring may be omitted if the arrangements are such, as shown by the dotted lines, that the full travel of the plunger is completed before the tumbler switch has reached the dead point; in this

position the tumbler contacts are in engagement, but there is a torsional stress giving a quick release as soon as the plug is removed.

5 In Fig. 5, the solid plunger is replaced by a piston 22, to which is attached a rod 23, enlarged at one part into a ring to receive the pip 17 of the tumbler. The rod 23 is shown supported by a guide 24.

10 The invention is not limited to the tumbler type of switch, but is applicable to any type of tumbler switch having a projecting handle.

Having thus described the nature of the 15 said invention and the best means I know of carrying the same into practical effect, I claim:

1. In combination, an electric switch, a casing for the switch, a handle operating the 20 switch contacts and projecting through the said casing, a wall socket, a plug adapted to engage in the said socket, a linearly sliding member engaging said handle, and a wing on said plug adapted on the insertion 25 of the plug in the socket to move said sliding member to close the switch contacts.

2. In combination, an electric switch, a casing for the switch, a handle operating the switch contacts and projecting through the 30 said casing, a wall socket, a plug adapted to engage in the said socket, a linearly sliding member engaging said handle, a wing on said plug adapted on the insertion of the plug in the socket to move said sliding member to close the switch contacts, and a spring 35 adapted to move said sliding member in the opposite direction when said plug is withdrawn from the socket.

3. In combination, an electric switch, a 40 casing for the switch, a handle operating the switch contacts and projecting through the said casing, a wall socket, a plug adapted to engage in the said socket, a tubular casing, a plunger slidably in said casing, and 45 means associated with said plunger and engaging said handle to close the switch contacts when said plug is inserted in said socket.

4. In combination, an electric switch, a 50 casing for the switch, a handle operating the switch contacts and projecting through the said casing, a wall socket, a plug adapted to engage in the said socket, a tubular casing, a

plunger slidable in said casing, means associated with said plunger and engaging said handle to close the switch contacts when 55 said plug is inserted in said socket, and a spring in said tubular casing to move the plunger and thereby operate the handle to open the said contacts. 60

5. In combination, an electric switch, a receptacle for the switch, a cover for the top of the receptacle having an opening, a handle operating the switch and projecting through said opening, a socket on the said 65 cover, a plug adapted to be inserted in said socket, a tubular casing on the cover, a plunger slidably in said tubular casing and engaging with said handle, and means associated with the plug adapted to move said 70 plunger and close said switch when the plug is inserted in the socket.

6. In combination, an electric switch, a receptacle for the switch, a cover for the top of the receptacle having an opening, a handle operating the switch and projecting through said opening, a socket on the said 75 cover, a plug adapted to be inserted in said socket, a tubular casing on the cover, a plunger slidably mounted in said tubular 80 casing and engaging with said handle, and a wing on said plug to engage and move said plunger to close said switch when the plug is inserted in the socket.

7. In combination, an electric switch, a 85 receptacle for the switch, a cover for the top of the receptacle having an opening, a handle operating the switch projecting through said opening, a socket on the said cover, a plug adapted to be inserted in said socket, a 90 tubular casing on the cover, a plunger slidably mounted in said tubular casing and engaging with said handle, a wing on said plug adapted to engage and move said plunger and close said switch when the plug 95 is inserted in the socket, and a spring in said tubular casing adapted to open the switch when the plug is withdrawn from the socket.

In testimony whereof I have signed my 100 name to this specification in the presence of two subscribing witnesses.

D. M. EDWARDS.
